METHOD AND APPARATUS FOR REMOVING
PELICLE FROM FILBERT NUT KERNELS

Edwin H. Schoolcraft, Forest Grove, Oreg., assignor to Northwest Nut Growers, Portland, Oreg., a corporation of Oregon

Application November 1, 1949, Serial No. 124,932

4 Claims. (Cl. 146—231)

1

This invention relates to the removal of the pellicle or the skin from nut meats, and, more specifically, to the removal of the pellicle from the kernel of filbert nuts.

As is well known, the skin or pellicle of a filbert nut is brown in color, resembling in color and somewhat in texture the skin of an almond or peanut. Various processes and means have been employed for removal of this skin from filbert nut kernels. While the kernel of the filbert nut is more or less spherical in general shape, its surface also has irregularities such as valleys and adjacent rounded high points, which prevent the removal of the skin entirely by mechanical means without grinding away the surface of the kernel. Soaking of the filbert kernel softens the skin, particularly if an alkaline solution is used. Accordingly one method which has been employed extensively in the past for removing filbert skins has included immersing the filbert kernels in a heated alkaline solution. One objectionable feature of this method, however, is that the hot solution causes some of the brown color from the skin to be transferred to the surface of the kernel resulting in a certain amount of discoloration of the kernel and thus detracting from the appearance of the treated kernel.

Another and somewhat more satisfactory method of removing filbert skins is the method described in U. S. Letters Patent No. 2,273,183, issued February 17, 1942 to Edward B. Edes, and entitled "Process for the Removal of Skins of Filbert Nuts." In accordance with the method described in this patent, the filbert kernel is first subjected to immersion in a cold weak alkaline solution and then, after rinsing in water, is immersed in a weak acid solution, following which the loosened skin is removed by forcible action of water. However, this improved process is somewhat lengthy and troublesome and thus more or less expensive.

The object of the present invention is to provide an improved method and means for removing the filbert skin, and, particularly, for removing the skin from the filbert kernel by the use of water alone, thus eliminating the necessity of subjecting the kernel to an alkaline bath, or to an alkaline bath and subsequent acid bath.

Attempts have been made heretofore to remove filbert skins by bringing the kernels into contact with jets of water under pressure. These attempts have proven unsatisfactory chiefly due to the following reasons:

1. Jets of water which were strong enough to dislodge the skin from the kernel also frequent-

2

ly removed portions of the outer surface of the kernel, producing rough surface spots on the kernel and consequently giving an unsatisfactory appearance to the treated kernel.

2. Prolonged contact of the kernel with water, particularly if portions of the kernel surface have been broken off by the action of the water jets, causes the water to soak into the kernel surface. As a result an increased drying action is then necessary in order to rid the kernel of the moisture and prevent mold or other deterioration taking place. However, the necessary increased drying action causes the kernel also to lose some of its oil and flavor.

3. Accordingly, a further and specific object of the present invention is to provide an improved method and means for removing the filbert skin by forcible use of water alone, but in such manner that no damage to the surface of the kernel will occur and with the total period during which the kernel is in contact with the water reduced to such a limited time that no appreciable penetration of water into the kernel will occur, thus enabling the final drying of the kernel to be accomplished quickly and without detriment to the kernel.

4. In the method and means which I employ in the carrying out of this invention, and by which I have been successful in accomplishing the above objects and also in attaining other incidental advantages, the nut kernels are subjected for a brief period, in the first stage of the treatment, to a succession of jets of water, but the kernels are kept rapidly moving in such manner that while the jets are strong enough to loosen and dislodge the skin from the kernel no opportunity is given the jets to cut into the kernel surface. Then the kernels pass through a second stage of treatment in which they are also engaged by jets of water but in which the force of the jets is reduced, the purpose of the jets in the second stage being merely to remove any portions of the loosened skin which still remain on the kernel. Finally, after as much of the water has drained off from the surface of the kernel as possible, the kernel is subjected to a quick drying action. The entire operation takes place in the matter of minutes, before there has been time for any appreciable penetration of the water into the kernel to take place.

5. The manner in which, and the preferred means by which, this treatment is accomplished will now be explained more clearly with reference to the accompanying drawings in which:

Fig. 1 is a more or less diagrammatic side ele-

3

vation of part of the entire apparatus; and Fig. 1A is a corresponding side elevation of the remaining part of the entire apparatus;

Fig. 2 is a transverse vertical section taken on line 2-2 of Fig. 1, but drawn to a larger scale;

Fig. 3 is an enlarged fragmentary section corresponding in part to Fig. 2;

Fig. 4 is a fragmentary plan view of the portion of the apparatus in which final draining of the water from the kernel takes place, the view being taken on line 4-4 of Fig. 1;

Fig. 5 is a transverse vertical section of the drier portion of the apparatus taken on line 5-5 of Fig. 1A.

Fig. 6 is a fragmentary elevation, partly in vertical section of the intake end of the drier section of my apparatus;

Fig. 7 is a detailed drawing of one of the rolls on which the nut kernels are carried during the skin-removing and draining treatment of the 20 kernels; and

Fig. 8 is a vertical section on line 8-8 of Fig. 1A but drawn to a larger scale.

The means which I have developed for the carrying out of my invention may be considered as divided into four parts or sections representing four stages in the complete skin-removing treatment given the filbert kernel. In Fig. 1 and Fig. 1A these four sections or portions of the apparatus are indicated by the reference characters A, B, C and D respectively.

Briefly, the action which takes place in each section may be described as follows:

In section A the kernel, while being moved rapidly in a manner hereinafter explained, is subjected to a series of strong jets of water. During this period the skin is loosened and a large amount of the skin is removed.

In section B the kernel, also while being similarly moved rapidly, is subjected to a further series of water jets, which, however, strike the kernel with less force and serve merely for the purpose of removing any remaining portions of the loosened skin which have survived the treatment in the first section.

In section C the water remaining on the kernel is given a chance to drain off while the kernel is rotated and moved forward.

Finally, in section D a drying action takes place to remove any remaining moisture from the surface of the kernel.

The different portions or sections of the apparatus and the operation of each will now be described more fully. Section A comprises one or more longitudinally-extending jet chambers 10, depending upon the volume of nut kernels to be handled. In the apparatus illustrated (see Fig. 2) there are five such chambers in section A. These chambers extend the entire length of this section A and the nut kernels pass from one end to the other. The bottom of each chamber is formed by a pair of rotating rolls 11, and a stationary housing above the rolls provides the vertical side walls 12 and an arched top wall 13 in each chamber. The chambers are identical in size and shape and therefore a description of one such chamber will suffice.

The two rolls 11, which form the bottom of the chamber, rotate in unison in the same direction, thus clockwise as viewed in Figs. 2 and 3. The rolls are mounted in suitable bearings (not shown) at each end, and are connected together, and also connected with a driving mechanism, by suitable gears. Each roll 11 has a spiral ridge 15 extending on its cylindrical surface from one end

4

of the roll to the other. As will be apparent, when the nut kernel is delivered onto the pair of rolls at the intake end of the chamber 10, the rotation of the rolls in the same direction causes the kernel to rotate with the rolls, and the engagement of the kernel with the spiral ridges on the rolls causes the kernel also to be moved forward longitudinally along the rolls from the intake to the outlet end of the chamber.

A series of jet nozzles 16 extend through the top of the chamber 10 and are connected to a delivery pipe 17. Water at a constant predetermined and adjustable pressure is delivered from a suitable pump (not shown), and suitable and well known means is employed by which the adjusted desired water pressure is maintained in the delivery pipe 17. Thus the force of the water jets discharged from the nozzles 16 down into the chamber 10 is maintained at a constant predetermined amount. The nozzles 16 are equally spaced along the center top of the chamber. However, the nozzle channels instead of being directed vertically downward and thus against the top of a nut when positioned over the center groove between the two rolls 11 at the bottom of the chamber, are directed somewhat to the left as viewed in Figs. 2 and 3. Consequently the jets from these nozzles strike the kernel (indicated by K in Fig. 3) off center, with the obvious result of increasing the rotational speed of the kernel and also of causing the kernel to bounce around somewhat during its course through the chamber 10. This off-center direction of the nozzle jets is an important feature of the invention and further reference will be made to this feature later.

35 ther reference will be made to this feature later.
The size of the chamber 10 and the size of the
rolls 11 which form the bottom of the chamber
are important. In order to prevent bouncing of
the kernel too far to one side or the other in the
chamber, I have found that the width of the
chamber should not exceed a maximum of two
and one-half times the approximate diameter of
the filbert kernel and preferably should be
slightly less. Also the height of the chamber
should not be too great so that up and down
40 bouncing of the kernel may be properly restricted
and too much fluctuation in the distance be-
tween the discharging end of the nozzles and the
points of impingement of the nozzle jets on the
kernel surface be avoided. I have found that the
45 height of the chamber, from the top line of the
rolls 11 to the center of the arched top wall,
should not exceed three and one-half times the
approximate diameter of the kernel. The diam-
eter of the rolls 11 is limited by the width of the
50 chamber. The space between the rolls should be
very narrow in order to prevent any possibility of
the kernel being pushed down between the rolls.
In the successful carrying out of my invention all
55 of these dimensions are more or less critical.

60 Since filbert nut kernels generally average from $\frac{5}{8}$ of an inch to $\frac{7}{8}$ of an inch in diameter I have found it most satisfactory to have the rolls 11 approximately $1\frac{1}{2}$ inches in diameter and the spiral ridge 15 extending to a height of $\frac{1}{16}$ inch beyond the roll surface. The rolls are positioned so that their respective ridges will be exactly opposite each other, and I have found that a clearance between the ridges of approximately .006 of an inch is satisfactory and preferable. Consequently I make the maximum spacing between the surfaces of the adjacent rolls $\frac{1}{8}$ inch plus .006 inch or .131 inch. Since the rolls rotate in unison their ridges will always be opposite each other, thus preventing any possibility of a kernel

becoming pinched between the ridges of the two rotating rolls at the bottom of the chamber.

The slope of the spiral ridge 15 on the rolls may be varied, but in my apparatus as illustrated, I use a 60° spiral (see Fig. 7). The slope of the spiral and the rate at which the rolls are rotated will of course determine the length of time required for the kernel to travel the length of the chamber 10. The chambers 10 may be of any desired length but I consider a length of approximately three feet to be satisfactory and preferable in my apparatus.

The nozzles 16 are spaced about one inch apart along the top wall of the chambers. Each nozzle has a discharge opening of .035 of an inch and I have found it satisfactory to have water at a pressure of 100 to 400 pounds per square inch discharged from the nozzles 16. In order to insure most satisfactory results both the amount of water pressure to be used and the minimum amount of time in which the kernel is to remain in transit through the chamber 10 (and thus the speed of rotation of the rolls 11) should be determined by trial for each grade of filbert nuts. Processed, inasmuch as there is some variation in the hardness of filbert nut kernels and pellicle as well as in the size of the kernels for different grades of filbert nuts. Generally it will be found that the size and spacing of the nozzles and the water pressure previously mentioned together with a transit period of twenty seconds required for the kernel to travel from the intake end to the outlet end of the chamber 10 will be sufficient and that during this period of travel most of the pellicle or skin will be removed from the kernel.

Preferably, although not necessarily, I make the spiral ridge 15 on each roll 11 in the form which I have illustrated in Fig. 7 and thus with the forward or leading edge 18 substantially vertical and the rear edge 19 having a slope of, for example, 45°. This rear sloping edge on the ridge prevents any possibility of particles from the kernel surface being broken off if the impact of a water jet against the kernel should momentarily cause a forward thrust to be given the kernel.

From the illustration in Fig. 3 it will be understood that the various angles of impingement of the water jets from the nozzles 16 with the surfaces of the kernels will practically always be acute angles. Furthermore, the impact of these jets with the surface of the kernel, together with the two directional motions imparted to the kernel by the rotating rolls and their spiral ridges, will keep the kernel continually and rapidly changing its position in the chamber 10. As a result, the impact blows delivered by the water jets against the kernel will be glancing blows of the type best suited to exert a peeling action, and since the points of impact of the jets on the kernel surface are constantly and rapidly shifting, the possibility that any jet will cut into or dig out a portion of the kernel surface beneath the pellicle is reduced to a minimum. In fact, as a result of the manner in which the kernel is moved about and is free to move about, during its travel through the chamber 10, the water pressure and jet force can be considerably increased beyond that which I have found necessary for the removal of the skin from the kernel with little or no damage to the kernel surface resulting. As indicated previously, the width and height of the chamber 10 limit any bouncing movement on the part of the kernel and thus prevent the kernel from staying out of the proper

range of the successive jets which act upon the pellicle. In the apparatus which I have illustrated, with the rolls 11 one and one-half inches in diameter and spaced apart a distance of .131 of an inch, I have found it very satisfactory to have the chamber 10 one and three-eighths inches wide and 1 1/8 inches high at the center of the arched top from the top line of the rolls.

When the kernel has reached the outlet end of the chamber 10 in the first section A of my apparatus, it is dropped down into the intake end of a subsequent and similar chamber in section B of the apparatus. Section B is a duplication of section A, the only difference being, as previously indicated, that the water pressure in the water-delivery pipes in section B is considerably reduced, and consequently the water jets in section B contact the kernel with much less force. The purpose of the travel of the kernel through this second section B of my apparatus is merely to complete the removal of any portions of the skin which may have survived the treatment in section A, and since such skin portions will at least have become soaked with water and partially removed in section A, less forcible water action is required in section B to complete the skin removing operation. Again in section B the speed with which the rolls are rotated, and thus the period of time for the travel of the kernel through this section B, can best be determined by trial, and it is preferable that the kernel should not be required to remain in section B any longer than necessary in order that the entire skin removing treatment may be accomplished in a minimum amount of time and also in order that the contact of the kernel with water will not extend over a prolonged period.

With some grades of filbert nuts the passage of the kernels through section B of my apparatus may be found unnecessary. Thus the treatment in section A may be adjusted so that all the skin will disappear from the kernel in that section. In such case section B could be removed from the apparatus and the kernel caused to pass directly from section A to section C. However, I consider it preferable, even when the filbert nuts are of such type that the skins are easily and safely removed entirely in section A nevertheless to continue the use of both section A and section B in my apparatus since only a brief additional time need be taken for the passage of the kernel through section B, and a greater margin of safety in the jet force in section A can be maintained to guard against any possibility of injury to the surface of the kernel by the water jets in section A.

From section B the nut kernel passes into section C of my apparatus. In sections A and B the pieces of skin, as they are removed from the kernel, are washed down through the slot between the two rolls at the bottom of each treating chamber with the water from the nozzle jets. However some of the water clings to the surface of the kernel and the purpose of having the kernel pass through section C of the apparatus is to have as much as possible of this surface water drained off from the kernel preparatory to the final drying of the kernel.

Section C comprises an open trough (Figs. 4 and 8) having sloping side walls 20 and 21 and with the bottom of the trough formed by a plurality of rolls 22 (thus four such rolls being shown in the apparatus illustrated). The length of the trough preferably is approximately the same as the length of the previous sections A and

B and thus I make this trough approximately three feet in length. The rolls 22 are similar to the rolls 11 in sections A and B, have similar spiral ridges on their cylindrical surfaces and are rotated in the same direction, causing the kernel to be rotated as well as moved forwardly along the trough. The rotation of the kernel of course aids in causing the water to leave the kernel surface. The rolls 22 in this section C can, if desired, be made larger in size and the trough can be of any convenient width and depth depending upon the desired capacity of the apparatus. It will be found that a surprising amount of water is drained off from the kernel as it passes through this section of the apparatus with the result that the final drying of the kernel in the last section of the apparatus is able to be accomplished more quickly and with the use of less drying heat.

From the draining trough or section C of the apparatus the kernel is delivered into the final drying section D. This drying section comprises a rotating drying tube 23 (Figs. 5 and 6) of any adequate size, for example having an interior diameter of twenty inches or more. This drying tube 23 has a spiral flange 24 along its inside wall extending from the inlet to the outer end of the tube. The tube 23 is rotated slowly and as the kernel is delivered from the trough into the inlet end of the tube 23 the rotation of the drying tube 23 causes the kernel to roll along the spiral flange 24 until it finally reaches the outlet end of the drying tube.

A forced draft of air is delivered into the tube 23 by means of a suitable blower, the end of the pipe from the blower being indicated by the reference character 25 in Fig. 1. This forced draft of air through the tube 23 speeds up the final drying of moisture from the kernel surface as the kernel is rolled along in its contact with the inside of the tube and with the spiral flange 24.

In order to aid further in the complete and rapid drying of moisture from the kernel surface, I provide a row of heating elements, preferably infra-red lamps 26, mounted on a stationary supporting member 27 extending longitudinally through the interior of the tube 23 as shown in Figs. 5 and 6. While other heating means might be used in the tube, I have found that the infra-red lamps, in combination with the forced draft of air through the tube, are most satisfactory in producing the desired complete drying of the kernel surface in a minimum period of time and without causing any excessive heating of the kernel. As is well known, an application of too much drying heat would impair the quality of the kernel and would greatly reduce the length of time the kernel could be kept in storage without becoming stale or rancid. From the outlet or delivery end of the drying tube 23 the kernel passes on to an endless conveyor 28 (Fig. 1) and thence to a suitable receptacle (not shown) for shipment or temporary storage.

The entire process of removing the filbert skin and drying the water from the kernel surface takes place in my apparatus within a total of a few minutes, and since the length of time during which the kernel is exposed to the forcible water action is so limited, the amount of water penetration into the kernel surface is kept at a minimum, and this of course in turn reduces the extent of the final drying action required.

Also, the entire operation, with the apparatus properly adjusted for the particular grade of nuts being processed, can take place automatically without danger of waste or damage and with a

minimum amount of skill and care required on the part of the operator; and the further fact that water alone is used, in place of the heretofore customary alkaline bath, rinsing water, etc., reduces the cost of the entire skin removing process.

Obviously various modifications could be made in the construction of the different parts of my apparatus within the scope of my invention, but the apparatus as illustrated and described, after extensive testing, I have found to be highly satisfactory and accordingly I regard the same as a preferred instrumentality for the carrying out of my invention.

I claim:

1. An apparatus for removing pellicle from filbert nut kernels including an elongated high pressure jet chamber approximately three feet in length, said chamber having side walls and a top wall, the bottom of said chamber formed by a pair of identical rotating rolls rotated in the same direction at the same peripheral speed, an identical spiral ridge on each roll extending forwardly with respect to the direction of rotation of said rolls, whereby the nut kernels, when delivered at the intake end of said chamber will be kept rotating and will be moved along by said rolls to the discharge end of the chamber, said pair of rolls at the bottom of said chamber spaced a slight distance apart along the bottom center line of the chamber, a series of identical high pressure jet nozzles spaced along the top wall in said chamber and delivering jets of water at a pressure of from 100 to 400 pounds per square inch downwardly into said chamber, the axes of the channels in said nozzles being identically inclined slightly against the direction of rotation of said rolls, whereby the jets from said nozzles will strike the nut kernels off center and in the direction of rotation of the kernels and will strike the kernels with glancing blows suited to exert a peeling action without cutting the kernel surface beneath the pellicle, the width of said high pressure jet chamber being not greater than $2\frac{1}{2}$ times the approximate average diameter of the nut kernels, a second jet chamber following said first mentioned high pressure jet chamber and substantially identical in size and shape to said first mentioned chamber, said second chamber having a bottom formed by a similar pair of spirally-ridged rotating rolls and a series of similarly inclined jet nozzles along the top wall, but said latter mentioned nozzles delivering jets of water at much lower pressure than said first mentioned nozzles for the purpose merely of removing pieces of pellicle still remaining on the kernels, and means for transferring the nut kernels immediately from the discharge end of said high pressure jet chamber to the intake end of said second jet chamber.

2. An apparatus for removing pellicle from filbert nut kernels including a plurality of elongated high pressure jet chambers, each of said chambers having side walls and a top wall, the bottom of each chamber formed by a pair of rotating rolls of identical size rotated in the same direction at the same speed, an identical spiral ridge on each roll extending forwardly with respect to the direction of rotation of said rolls, whereby the nut kernels, when delivered at the intake end of each chamber will be kept rotating and will be moved along by said rolls to the discharge end of the chamber, the pair of rolls at the bottom of each chamber spaced approximately $\frac{1}{8}$ inch apart along the bottom center line of

the chamber, a series of jet nozzles spaced at equal distances along the top wall in each chamber and delivering jets of water at pressure of from 100 to 400 pounds per square inch downwardly into each chamber, the axes of the channels in said nozzles being inclined slightly against the direction of rotation of said rolls, whereby the jets from said nozzles will strike the nut kernels off center and in the direction of rotation of the kernels, the width of each of said high pressure jet chambers being not greater than 2½ times the approximate average diameter of the nut kernels, the height of each of said chambers from the top line of said rolls being not greater than 3½ times said approximate average diameter of the nut kernels, a lower pressure jet chamber following each of said high pressure jet chambers and substantially identical to said first mentioned chambers with the exception that the jets from the nozzles in said second chambers are delivered at considerably lower pressure, and means for transferring the nut kernels from the discharge end of each of said high pressure jet chambers to the intake end of a low pressure jet chamber respectively.

3. The method of removing the pellicle from unsoaked filbert nut kernels, said method comprising subjecting the kernels to a succession of identical jets of water under predetermined pressure in excess of 100 pounds per square inch, each of said jets being strong enough to injure a kernel surface if impinged for more than an instant at a point on the surface in a direction in alignment with the radius to said surface point, keeping the kernels constantly in rotation and in motion while subjected to said jets, having said jets directed at a slight angle of inclination against the kernels in the main direction of rotation of the kernels, whereby each of said jets will strike the kernels successively with a glancing blow suited to exert a peeling action on the pellicle without cutting the kernel surface beneath the pellicle, subjecting the kernels to said jets only long enough to remove the pellicle from the kernels and not longer than one minute, and then quickly draining and drying the water from the surface of the kernels before any appreciable amount of water has had time to penetrate into the surface of the kernels.

4. The method of removing the pellicle from unsoaked filbert nut kernels, said method comprising subjecting the kernels to a succession of

identical jets of water under predetermined pressure of from 100 to 400 pounds per square inch, each of said jets being strong enough to injure a kernel surface if impinged for more than an instant at a point on the surface in a direction in alignment with the radius to said surface point, keeping the kernels constantly in rotation and in motion while subjected to said jets, having said jets directed at a slight angle of inclination against the kernels in the main direction of rotation of the kernels, whereby each of said jets will strike the kernels successively with a glancing blow suited to exert a peeling action on the pellicle without cutting the kernel surface beneath the pellicle, subjecting the kernels to said jets for considerably less than one minute and only long enough to remove substantially all of the pellicle from the kernels, then subjecting the kernels for an equally short period to a second set of jets similarly directed but under considerably less pressure while similarly keeping the kernels continually rotating, until any remaining portions of pellicle have been removed by said second jets, and then quickly draining and drying the water from the surface of the kernels before any appreciable amount of water has had time to penetrate into the surface of the kernels.
